By Two Attorneys,

G. W. Harris Inventor

C. Snow & Co.

UNITED STATES PATENT OFFICE.

GEORGE W. HARRIS, OF AKRON, OHIO.

DESIGN FOR A JAW FOR TACK-PULLERS.

SPECIFICATION forming part of Design No. 31,036, dated June 20, 1899.

Application filed May 26, 1899. Serial No. 718,444. Term of patent 14 years.

To all whom it may concern:

Be it known that I, GEORGE W. HARRIS, a citizen of the United States, residing at Akron, in the county of Summit and State of Ohio, 5 have invented and produced a new and original Design for a Jaw for Tack-Pullers, of which the following is a specification.

The invention relates to a new and original design for a jaw for tack-pullers; and it has 10 for its object to provide a design of this character which will be both ornamental and useful.

The essential feature of the design resides in a jaw composed of two sides having straight 15 inner portions and provided with enlarged outer portions having curved edges and extended to form a tapering lip, and a minor feature of the design resides in the rectangular form of the tapered lip.

20 In the drawings, Figure 1 is a perspective view of a jaw, showing my new and original design. Fig. 2 is a side elevation of the same.

Referring to the drawings, 1 designates a 25 jaw composed of two sides 2, having straight inner portions and provided with enlarged

outer portions having curved upper and lower edges 5 and 6. The enlarged outer portions have their outer ends rounded to provide the upper curved edge 5, which is convexly curved. The lower edge 6 of the enlarged 30 outer portion of the jaw is approximately sigmoidally curved. At the outer end of the jaw, at the bottom thereof, is arranged a longitudinally-disposed tapering lip 7 of approximately 35 rectangular form and composed of straight sides and a straight outer transverse portion 8. The lower edges of the sides of the lip 7 are convexly curved and merge into the lower edges 6.

What I claim is—

40 The design for a jaw for tack-pullers, herein shown and described.

In testimony that I claim the foregoing as my own I have hereto affixed my signature in the presence of two witnesses.

GEORGE W. HARRIS.
